ABSTRACT OF THE DISCLOSURE

A clamping device for clamping a towel or the like flexible material and comprising an endless body, preferably parabolic-shaped, defining an open space therewithin and an elongated member extending transversely of said body across the space defined therewithin and having elongated slots in opposite end portions thereof through which opposed portions of said body extend, the distance between the proximate ends of the elongated slots being less than the distance between the opposed portions of the endless body, whereby the elongated member is slideable relative to the endless body.

This invention relates to a clamping device and more particularly to a clamping device for grasping a towel, sweater or the like flexible material.

Frequently during many different activities, it is highly desirable to have readily available a towel, sweater, or other flexible material. For instance, during a game of golf a towel is often used to dry the hands of a player, a club face or grip and the like, and accordingly, it is desirable to be able to attach a towel in a readily accessible place on the golf cart or golf bag for use during the game. Similarly but less frequent, there is a need for a sweater, jacket or the like to be readily available for use by a golfer or person engaged in a similar activity.

Many attempts have been made heretofore to provide clamping devices for towels, sweaters or the like flexible material, but these devices have proven to be unsatisfactory because they cause damage to the material being clamped, they have poor clamping action, or considerable difficulty is encountered in inserting and removing the flexible material from the device.

Accordingly, an object of this invention is the provision of a clamping device that overcomes the aforementioned deficiencies heretofore encountered and one which does not cause damage to the material being clamped, provides excellent clamping action, and may have towels, sweaters or the like flexible material easily inserted into or removed therefrom.

Some of the objects and advantages of the invention having been stated, others will appear as the description proceeds, when taken in connection with the accompanying drawing, in which—

FIG. 1 is a perspective of a golf cart and golf bag carried thereby with each having attached, respectively, thereto a clamping device in accordance with this invention for clamping a towel, sweater or the like flexible material;

FIG. 2 is an enlarged perspective of the clamping device attached to the golf cart handle of FIG. 1;

FIG. 3 is a sectional view taken substantially along line 3—3 of FIG. 2; and

FIG. 4 is an enlarged perspective of the clamping device attached to the golf bag of FIG. 1.

Referring in detail to the drawings wherein like numerals have been used where possible to refer to like parts, there is generally shown in FIG. 1 a golf cart 10 and golf bag 11 carried thereby. Clamping devices 12 and 13 of this invention are attached thereto and have a towel T and a sweater S clamped therein, respectively.

2

In general, the clamping devices 12, 13 comprise endless bodies 14, 15 defining open spaces therewithin and elongated members 16, 17 extending transversely of the endless bodies 14, 15, respectively, across the spaces defined therewithin and being slideable relative thereto.

More specifically, the clamping device 12 is particularly adapted for clamping hand towels and other relatively small items of flexible material and endless body 14, FIGS. 2 and 3, are preferably generally parabolic-shaped with a generally flattened top 14a and sides 14b, 14c which are integral with top 14a and curve symmetrically downwardly and converge into an apex at the bottom which is disposed directly below the center of top 14a. This parabolic shape accommodates a bunching of the flexible material in the center or apex while still applying a clamping force across substantially the full width of the material.

A ring member 20 is connected to top 14a at the center thereof for permitting the clamping device 12 to be readily attached to a suitable support, such as a golf cart handle as in FIG. 1, by an appropriate bracket means 21. The elongated member 16 is preferably an elongated bar member having elongated slots 22, 23 disposed in opposite end portions thereof, and the distance between the proximate ends of the elongated slots 22, 23 is less than the distance between sides 14b, 14c of the endless body 14 except at points closely adjacent the apex of sides 14b, 14c. The elongated bar member 16 extends transversely of the endless body 14 with sides 14b, 14c of the endless body 14 extending through the elongated slots 22, 23 whereby the elongated bar member 16 is slideable relative to the endless body 14 and in particular, slideable in a direction toward and away from the apex of the parabolic-shaped endless body 14 to clamp the towel between the bar member 16 and the sides 14b, 14c at the apex thereof. The portion of the elongated bar member 16 between sides 14b, 14c of the endless body 14 is preferably provided with undulated, irregular or serrated opposite side edges 24, 25 for increasing the frictional contact with the flexible material clamped in the device 12. Preferably, these serrated side edges 24, 25 project outwardly beyond the endless body 14, as best shown in FIG. 3, to deflect the flexible material outwardly of the endless body 14 to improve the clamping action of the device 12.

It is readily noted that the elongated bar member 16 divides the open space defined within the endless body 14 into two portions. A towel or other like flexible material is clamped into the clamping device 12 by threading the flexible material through one portion of the open space and back through the other portion whereby the flexible material is clamped between the elongated bar member 16 and the endless body 14 by frictional contact therewith. As stated above, the apex of the parabolic-shaped endless body 14 provides for bunching of the flexible material between the elongated bar member 16 and the endless body 14 and also the converging sides 14b, 14c guide elongated bar member 16 in its movement along body 14 while maintaining the elongated bar member 16 substantially horizontal across the endless body 14. The flexible material is easily removed from the device 12 by sliding the elongated bar member 16 in a direction away from the apex of the parabolic-shaped endless body 14 whereupon the flexible material may be easily dethreaded from the device 12. It will be further noted that gravity will act on the flexible material and clamping device 12 to maintain proper clamping of the flexible material during use of the device 12.

Referring now to FIG. 4, clamping device 13 is shown attached to the golf bag 11 of FIG. 1 and differs primarily in size and shape from the clamping device 12. Endless body 15 of clamping device 13 has a generally upwardly

curved or domed top 15a and is of larger size than clamping device 12 for accommodating relatively large items of flexible material, such as sweaters, jackets, and coats. Endless body 15 is also preferably generally parabolic-shaped similarly to endless body 14 with sides 15b, 15c converging downwardly to an apex. A ring member 30 is connected to the center of top 15a for attachment of endless body 15 to golf bag 11 by attachment means 31.

The elongated bar member 17 is structurally similar to the elongated bar member 16 of clamping device 12 except larger in size and includes elongated slots 32, 33 disposed in opposite end portions thereof with the distance between the proximate ends of the elongated slots 32, 33 being less than the proximate distance between sides 15b, 15c of the endless body 15 except at points closely adjacent the apex of sides 15b, 15c. The elongated bar member 17 extends transversely of the endless body 15 with sides 15b, 15c of the endless body 15 extending through the elongated slots 32, 33 whereby the elongated bar member 17 is slideable relative to the endless body 15 and in particular, slideable in a direction toward and away from the apex of the endless body 15. Also, opposite sides 34, 35 of elongated bar member 17 are preferably serrated to provide an increased frictional grip on the flexible material.

Clamping device 13 is used the same as clamping device 12 and also provides for bunching of material in the center thereof while still applying a clamping force thereto across substantially the full width of the device.

In the drawing and specification there have been set forth preferred embodiments of the invention, and although specific terms are employed, they are used in a generic and descriptive sense only and not for purposes of limitation:

What I claim is:

1. A clamping device for clamping a towel or other flexible material to a golf cart, golf bag, or the like and comprising an endless body defining an open space there-

within, and including a parabolic shaped portion defining an apex, means connected to the body opposite said apex for attaching said clamping device to a support, and a linear elongated member extending transversely of said body across the space defined therewithin and having elongated slots in opposite end portions thereof through which opposed portions of said body extend, the distance between the proximate ends of the elongated slots being less than the proximate distance between the opposed portions of the endless body except at a point closely adjacent said apex whereby the elongated member is slideable relative to the endless body in a direction toward and away from said apex to provide for bunching and uniform clamping of the flexible material between said apex and said elongated member, said elongated member including opposite side edges facing outwardly from said open space, both of said side edges including serrations adapted to engage the flexible material to increase the frictional contact therebetween.

2. The clamping device as defined in claim 1 wherein said serrations project laterally beyond the endless body to deflect the material clamped outwardly of the endless body to improve the clamping action.
